LIFTING JACK

Harold W. Clark, Alliance, Ohio, assignor to
The Buckeye Jack Manufacturing Company,
Alliance, Ohio, a corporation of Ohio

Application November 30, 1928
Serial No. 322,644

11 Claims. (Cl. 254—102)

This invention relates to lifting jacks, and particularly to lifting jacks of the screw type. It is herein illustrated and described as applied to a jack for use with automobiles, although it 5 has numerous other applications.

In automobile work, particularly with the advent of the balloon tire, it is necessary that a jack having a very low retracted height and a relatively high lift be provided. For this reason 10 jacks of the double screw type have come into favor. Such jacks, while they provide the necessary range of height and the low retracted height, have been open to numerous objections. Various schemes for insuring that the several screws may 15 be extended to the utmost have been proposed, but most of them are open to the objection that they are complicated or are expensive to manufacture.

A further disadvantage in jacks of this type has 20 been that the elevating mechanism is close to the top of the jack, so that even a light turning effort applied to the handle has been sufficient to turn the jack over. This defect is particularly noticeable on rough roadways. Such jacks have 25 also been open to the objection that the screws and bearings have been unprotected and likely to wear and "cut out" quickly, because of sand and grit.

I provide a jack of the screw type which has 30 a very low center of gravity, and in which the power is applied near the base, which may be manufactured at a very low cost, and in which all of the parts are adequately protected. The elevating mechanism is simple and compact and 35 is not in any danger of getting out of order.

In the accompanying drawings illustrating the present preferred embodiment of the invention,

Figure 1 is a side elevation of the jack partly broken away, in elevated position;

Fig. 2 is a transverse vertical section through the jack, the screws being in retracted position;

Fig. 3 is a top plan view;

Fig. 4 is a horizontal section taken on the line IV—IV of Fig. 2, and

Fig. 5 is a similar view taken on the line V—V of Fig. 2.

The jack shown in the drawings comprises a standard 2 of cylindrical form having an integral base 3. The top face of the standard supports a ball bearing 4 which, in turn, carries a nut 5. A metal sleeve 6 is welded to the nut as indicated at 7, and this sleeve extends downwardly over the standard 2, terminating adjacent the base 3. The sleeve 6 is journaled on the standard at 8 and 9 so that it is freely rotatable thereon, but

holds the nut in axial alignment with the standard.

A driven bevel gear 10 is welded to the bottom of the sleeve 6 as indicated at 11. This gear meshes with teeth 12 formed on one end of a 60 driving member 13. The driving member is journaled in a barrel 14 formed integral with the base 3. The driving member is provided with a socket 15 for the reception of a jack operating handle. It has a body portion 16 which lies in 65 the barrel, and the projecting portion on which the teeth 12 are formed is of the same diameter. The socket 15 is larger than the body portion 16 so that a shoulder bearing against one end 70 of the barrel 14 is provided.

By reason of the fact that the projecting portion carrying the teeth 12 is at least as small in diameter as the body portion 16, the driving member 13 may be slid into the barrel 14. It 75 is held in place by a split ring 16 which is pressed into a groove formed in the driving member after the driving member has been put in place.

By reason of the fact that the driving mechanism is adjacent the base, the center of gravity 80 of the jack is materially lowered and the danger of tipping the jack is materially decreased. This is due not only to the low center of gravity, but also the fact that the turning moment applied by the handle is effective very near to the point 85 of support.

The sleeve 6 provides a very useful effective grip whereby the nut 5 may be rotated for raising or lowering the jack by hand to any extent desired. This makes it much easier to preliminarily adjust the jack to near the desired height, and the 90 raising or lowering can be effected by hand at high speed.

The nut 5 engages a primary lifting screw 17. This screw is movable up or down within the hollow standard 2 and is provided with diametrically spaced lugs 18 adjacent its bottom. During the intermediate portion of the travel of the screw 17, the lugs 18 are engaged by ribs 19 formed on the inside of the standard, which ribs positively prevent rotation of the screw 17, whereby 95 rotation of the nut 5 causes the screw to raise or lower. The screw 17 is hollow and is threaded at its upper end to accommodate a secondary screw 20 having a load-engaging saddle 21. When the screw 17 reaches the upward limit of 100 its travel, the lugs 18 clear the tops of the ribs 19, thus leaving the screw 17 free to rotate. The upward movement of the screw 17 is terminated by the fact that the thread of the screw is terminated a sufficient distance from the bottom 110

so that it locks in the nut just after the lugs 18 clear the ribs 19. Continued rotation of the nut 5 therefore causes the screw 17 to rotate with it, and since the saddle 21 is engaged by the load, thus preventing rotation of the screw 20, the screw 20 is threaded upwardly to further raise the load.

When the load is to be lowered, it is desirable that the secondary screw 20 be actuated first. It sometimes happens that the friction of the small screw in its nut is greater than the friction of the large screw in its nut. If such is the case, the primary screw 17 reaches the bottom of its travel while the secondary screw 20 is still extended somewhat. Provision is made for such occasion, the primary screw being rotatable in its bottom position, and being held against rotation only by frictional means arranged to oppose rotation of the screw more strongly in one direction than in the other. The ribs 19 terminate a short distance above the base so that in the bottom position of the screw 17, the lugs 18 lie clear of the ribs 19.

When in this position one of the lugs is engaged by a coil spring 22 which is nested in the standard 2 and is provided with an inwardly projecting end 23. During lowering, the screw 17 tends to rotate counter-clockwise as viewed in Fig. 5. When clear of the ribs, such rotation is permitted. One of the lugs 18 strikes the projecting end 23 of the spring 22 and the spring, by reason of the direction in which it is wound, is relatively free to rotate within the standard 2, so that the screw 17 rotates with the nut 5 and causes lowering of the secondary screw 20. When the jack is raised the screw 17 tends to rotate in a clockwise direction, as viewed in Fig. 5, but one of the lugs 18 then strikes the other face of the projecting end 23 of the spring. This tends to expand the spring outwardly, and the free end 24 strongly engages the inner face of the standard 2, and provides considerable resistance against rotation of the screw 17. This resistance is sufficient to insure rotation of the nut 5 relative to the screw 17, thus raising the screw to a point where the lugs 18 engage the ribs 19. The lugs 18 are beveled off at the tops as indicated in Fig. 4, so as to insure that they will not lock underneath the ribs 19.

A spring 25, similar in all respects to the spring 22, is placed in the standard above the ribs 19, but in the opposite direction, as will be seen by a comparison of Figs. 4 and 5. When the screw 17 reaches the top of its travel, one of the lugs 18 engages the projecting end 26 of the spring 25 and by reason of the direction in which the spring is wound, it is readily rotated clockwise with the screw 17 as the secondary screw 20 is threaded outwardly.

When the jack is lowered, one of the lugs 18 engages the opposite face of the spring end 26, whereupon the free end 27 of the spring bears strongly against the inner face of the standard and thus insures that the screw 17 will be threaded downwardly.

I have illustrated and described a present preferred embodiment of the invention as applied to an automobile jack. It will be understood, however, that the invention is not limited to the form shown, but may be otherwise embodied within the scope of the following claims.

I claim:

1. A jack comprising a standard, a lifting screw movable within the standard, a rotatable nut for raising and lowering the screw, means on the standard for positively limiting rotation of the

screw relative to the standard during a portion of its movement, and friction means for limiting rotation of the screw during another portion of its movement, including a spring coiled in said standard having means engageable by the screw tending to coil or uncoil the spring, depending on the direction of screw rotation, so that the spring rotates freely in the standard or engages it frictionally.

2. A jack comprising a standard, a lifting screw movable within the standard, a rotatable nut for raising and lowering the screw, means on the standard for positively limiting rotation of the screw relative to the standard during a portion of its movement, and friction means for limiting rotation of the screw during another portion of its movement, including a resilient member lying within said standard having means engageable by the screw tending to expand or contract the resilient member, depending on the direction of screw rotation, so that said member frictionally engages the standard or rotates freely therein.

3. A jack comprising a standard, a lifting screw movable within the standard, a rotatable nut for raising and lowering the screw, means on the standard for positively limiting rotation of the screw relative to the standard during a portion of its movement, and a spring coiled in said standard having means engageable by the screw tending to coil or uncoil the spring, depending on the direction of screw rotation, so that the spring rotates freely in the standard or engages it frictionally.

4. A jack comprising a standard, a lifting screw movable within the standard, a rotatable nut for raising and lowering the screw, a lug on the screw, the standard being shaped to engage the lug during a portion of the travel of the screw and limit rotation during such portion of the travel, and a spring coiled in said standard having means engageable by the lug tending to coil or uncoil the spring, depending on the direction of screw rotation, so that the spring rotates freely in the standard or engages it frictionally.

5. A jack comprising a standard, a lifting screw, a rotatable nut for raising or lowering the screw, means for positively limiting rotation of the screw during the intermediate portion of its travel, and springs coiled within said standard at the ends of the travel of the screw, said springs having means engageable by the screw tending to coil or uncoil the springs, depending on the direction of screw rotation, so that the springs rotate freely in the standard or frictionally engage it.

6. A jack comprising a standard, a lifting screw, a rotatable nut for raising or lowering the screw, means for positively limiting rotation of the screw during the intermediate portion of its travel, and friction means for limiting the rotation of the screw at the top and bottom portions of its travel, including springs coiled within said standard adjacent the ends of the screw travel, said springs having means engageable by the screw tending to coil or uncoil them, depending on the direction of screw rotation, so that the springs rotate freely in the standard or frictionally engage it, the respective springs being effective to engage the standard frictionally on rotation of the screw in opposite directions.

7. A jack comprising a standard, a lifting screw, a rotatable nut for raising or lowering the screw, means for positively limiting the rotation of the screw during a portion of its travel, friction means for limiting rotation of the screw at the top of its travel, including a spring coiled

within the standard at the top of the screw travel, having means engageable by the screw for coiling or uncoiling the spring on rotation of the screw in opposite directions whereby the spring rotates 5 freely in the standard or engages it frictionally to restrain rotation of the screw in one direction.

8. A jack comprising a standard, a lifting screw, a rotatable nut for raising or lowering the screw, means for positively limiting the rotation 10 of the screw during a portion of its travel, friction means for limiting rotation of the screw at the bottom of its travel, including a spring coiled within the standard having means engageable by the screw for coiling or uncoiling the spring to 15 permit free rotation of the screw in one direction and frictionally restrain it in the other direction.

9. A jack comprising a standard, a lifting screw, a rotatable nut for raising or lowering the screw, means for positively limiting the rotation 20 of the screw during a portion of its travel, friction means for limiting rotation of the screw at the top and bottom of its travel, including springs coiled within said standard having means engageable by the screw for contracting or expand- 25

ing them, depending on the direction of screw rotation, whereby the springs rotate freely in the standard or engage it frictionally.

10. The combination with a standard, a threaded tube reciprocable in the standard and a nut for actuating the tube, of means for preventing rotation of the tube in the standard during part of its movement, and a spring coiled in said standard adjacent one end of the tube travel and having means engageable by the tube for coiling or uncoiling it, depending on the direction of tube rotation, whereby the spring rotates freely in the standard or engages it frictionally. 80

11. The combination with a jack having a standard, a threaded tube therein, and a nut surrounding the tube and rotatable on the standard, of a spring curved around said tube having means engageable by the tube for expanding or contracting the spring, depending on the direction of tube rotation, so that the spring rotates freely in the standard or engages it frictionally to restrain rotation of the tube in one direction. 85 90 95
